UNITED STATES PATENT OFFICE.

JOHN CHARVAT, JR., OF CHICAGO, ILLINOIS.

PERCOLATOR.

1,285,621.

Specification of Letters Patent. Patented Nov. 26, 1918.

Application filed May 6, 1918. Serial No. 232,828.

To all whom it may concern:

Be it known that I, JOHN CHARVAT, Jr., a citizen of the United States, and a resident of Chicago, in the county of Cook and State 5 of Illinois, have invented certain new and useful Improvements in Percolators, of which the following is a specification.

This invention relates to percolators, and the primary object of this invention is to 10 provide a percolator embodying a substantially cylindrical foraminous body composed of a pair of detachably connected sections which are adapted to contain ground coffee and also to provide suspending means for 15 suspending the body of the percolator within a suitable container, in a horizontal manner to permit swinging movement of the body within the container and also to permit rotary movement of the container about 20 a horizontal axis, which movement together with the swinging movement will be imparted to the percolator by the boiling action of the water within the container, and further by mounting the body of the perco- 25 lator within the container in a horizontal plane a greater surface area thereof will be presented to the upwardly traveling boiling water, increasing the percolating action.

Other objects of the invention will appear 30 in the following detailed description, taken in connection with the accompanying drawings forming a part of this specification and in which drawing:

Figure 1 is a sectional view through a 35 container showing the improved percolator in place therein.

Fig. 2 is a longitudinal section through a modified form of the percolator and

Fig. 3 is a section on the line 3—3 of 40 Fig. 2.

Referring more particularly to the drawing, A designates a suitable container for water which is placed upon a stove or suitable fire for boiling the water therein, and 45 the percolator structure is generically indicated by the letter B.

The percolator structure B comprises the foraminous substantially cylindrical body 1, the ends of which taper or converge to- 50 ward the central axis of the body as clearly shown in the drawing. The body 1 is composed of sections 2 and 3 which are detachably connected by means of pins 4 carried by the section 3 and bayonet slot-shaped depres- 55 sions 5 formed in a metal ring 6 which is

carried at the end of the section 2 in which the inner end of the section 3 seats.

The body 1 has eyes 7 and 8 rotatably connected to its ends and at the central axis of the body. Flexible suspending chains 60 9 are connected to the eyes 7 and 8 and they have hooks 10 attached to their upper ends, which hooks engage over the edge of the portion of the container 1 surrounding the inlet 11 of the container. The hooks 10 65 are preferably shaped to snugly fit against and conform to the curvature of the surfaces, both inner and outer, of the portion of the container surrounding the inlet 11 thereof. 70

In Figs. 2 and 3 of the drawing, a modified form of the percolator body is shown. This modified form is composed of sections 20 and 21 which are formed from thin sheet metal and when connected provide a 75 substantially cylindrical body the ends of which taper toward the central axis thereof. The sections 20 and 21 are provided with a plurality of perforations indicated at 22 to render these sections foraminous, 80 and to permit of the percolation of the contents of the body.

The section 20 is provided with an in- 85 struck annular bead 23 near its open end which forms a stop for limiting the insert- 85 ing movements of the open end of the section 21 into the open end of the section 20. The section 21 carries pins 23, which pins engage in bayonet slot-shaped outstruck 90 portions 24 formed on the section 20 near its open end, for connecting the sections 20 and 21 to prevent accidental disconnection thereof during the use of the percolator.

Attaching eyes 25 are rotatably connect- 95 ed to the ends of the body formed in the sections 20 and 21 and flexible suspending chains or cords 26 are connected to the eyes 25. The chains 26 are identical in construction with the chains 9, and they have hooks carried at their upper ends for en- 100 gagement with the portions of the container A surrounding the inlet opening of the same, so as to suspend the body formed in the sections 20 and 21 within a container in a horizontal plane, for swinging action 105 and also for rotary action about the horizontal central axis of the body. This move- ment of the percolator body within the container permits of the efficient percolation of the contents of the body, continually 110

keeping the contents of the percolator body in an agitated state during the boiling of the water within the container and consequently permits of the utilization of all of 5 the flavoring ingredients of the contents of the body in the liquid, or coffee, being prepared within the container.

Having thus fully described the invention, what is claimed is:

- 10 1. In a percolator, a substantially cylindrical foraminous body, attaching eyes rotatably connected to each end of the body at its central axis, flexible suspending means connected to said attaching means to support said body in a horizontal position within a container, to permit the body to swing within the container, the connection between
- 15

said attaching eyes and said body allowing the body to rotate about a horizontal axis.

2. In a percolator, a substantially cylindrical foraminous body having its end portions tapering toward the central axis thereof, attaching eyes rotatably connected to each end of said body at its central axis, flexible suspending means connected to said 25 eyes, hooks carried by the free ends of said suspending means, said body composed of a pair of detachably connected sections, said hooks and suspending means adapted to suspend the body horizontally within a 30 container to permit swinging movement of the body and rotary movement about a horizontal axis longitudinally of the body.

JOHN CHARVAT, Jr.
